UNITED STATES PATENT OFFICE.

AUGUSTUS F. HARTER, OF CHICAGO, ILLINOIS, ASSIGNOR TO CRIBBEN & SEXTON COMPANY, OF CHICAGO, ILLINOIS, A CORPORATION OF ILLINOIS.

STOVE OR RANGE.

Application filed October 11, 1926. Serial No. 140,880.

This invention pertains particularly to the oven construction in ranges, such as gas ranges.

The primary object is to provide an improved oven construction which is staunch, durable, easily assembled and which presents flush joints.

The invention is illustrated in its preferred embodiment in the accompanying drawings, in which—

Fig. 1, is a broken elevational view of a gas range embodying the invention; Fig. 2, a broken vertical sectional view, no an enlarged scale, taken as indicated at line 2 of Fig. 1; Fig. 3, a broken horizontal section at one of the front corners of the oven, the section being taken as indicated at line 3 of Fig. 1; Fig. 4, a broken vertical section taken as indicated at line 4 of Fig. 2, this section being parallel with the plane of the oven front; Fig. 5, a broken perspective view showing the front portion of the top plate of the oven; Fig. 6, a broken inner perspective view showing one of the corners of the front frame of the oven-unit; Fig. 7, a sectional perspective view looking into the inner, upper corner of the oven; and Fig. 8, a broken vertical sectional view, showing a rear upper corner portion of the oven.

In the illustration given, A designates an oven-unit of a gas range; and B designates the cooking-top of the range.

The oven-unit is shown provided with a front frame A' equipped with an upper door A² of a baking oven and with a lower door A³ for the broiler oven.

The baking oven and broiler oven are constructed as a unit. This unit comprises, in addition to the front frame A', sheet-metal side plates 1, a sheet-metal top plate 2, and a sheet-metal rear wall 3.

The side plates 1 are provided near their upper ends with inwardly offset margins 1^a, from the upper edges of which extend inwardly offset margins 1^b; also, said plates are provided with inwardly offset margins 1^c and inwardly offset margins 1^d, which extend parallel with the plane of the front frame A'. The flanges 1^b may be omitted, if desired.

The top plate 2 is provided at its lateral edges with downwardly turned flanges 2^a, and at its rear edge with a downwardly turned flange 2^b. As shown in Fig. 5, the top plate 2 is offset downwardly at its front portion to provide a depressed margin 2^c,

from which depends an attaching flange 2^d which is disposed parallel with the plane of the front frame A' of the oven-unit. The top member 2 is notched at the corners, as indicated at 2^e.

The front frame A' of the oven-unit, which preferably is of cast metal, presents a front face 4 and a rearwardly extending outer flange 4^a. One of the door-openings is indicated at 4^b, and the metal of the frame is offset inwardly as indicated at 4^c, to provide the seat for the door.

The wall 4 of the frame is provided at its inner side with tapped lugs 4^d, as many as may be desired, which are adapted to receive cap screws 5 which connect the flanges 1^d of the side plates of the oven and flange 2^d of the top plate of the oven with the oven-front. The cap screws pass through slots, or large openings 6, with which the attaching flanges of the sheet-metal plates are provided. The frame A' is shown provided, also, with lugs 7, which are of use in holding the lining-plates of the oven in position.

As will be noted from Figs. 2 and 7, the upper front corners of the side plates 1 are notched as indicated at 1^e to provide the necessary clearance for the flange 2^b of the top plate.

In assembling the members of the oven-unit, the inwardly offset portions 1^c of the side plates and the downwardly offset portion 2^c of the top plate fit within the rearwardly turned flange 4^a of the front frame A', so as to provide flush joints; and the downturned lateral flanges of the top plate embrace the inwardly offset margin portions 1^a of the side plates, as will be best understood from Fig. 7. The tapped lugs 4^d of the frame A' space the inwardly turned flanges 1^d and 2^d with relation to the frame A'; and the cap screws 5 enter the tapped lugs and secure the parts together.

The front edge portions 2^f of the lateral flanges 2^a of the top plate abut against the rear edge of the flange 4^a of the frame A'.

As shown in Fig. 8, the side plates 1 are provided at their rear edges with inwardly offset margins 1^f, which embrace the rear plate 3 of the oven. The lateral flanges 2^a of the top plate 2 are secured, by bolts 8, to the portions 1^a of the side plates 1. As appears from Fig. 8, the oven is shown equipped at its rear portion with a standard-plate 9, connected by means of bolts 10, which serve

also to connect the side plates, top plate, and rear plate of the oven.

Linings for the oven-unit may be provided in any suitable way. In Fig. 2, 10 designates a lining plate spaced some distance below the top plate 2, this plate being supported by lugs 7. In Fig. 3, is shown one of the lateral lining plates 11 of the oven, supported by lugs 7. The upper portion of the lining plate 11 appears again in Fig. 4.

From the description given, it will be understood that the side plates and top plate of the oven are flush with the perimeter of the front frame A'; also, that the inturned flanges of the side plates and top plate of the oven-unit are securely fastened to the front frame by means of the concealed cap-bolts 5.

20 The construction described is staunch and durable, and may be easily assembled. The oven-unit thus constructed presents a neat appearance, with flush joints.

25 The foregoing detailed description has been given for clearness of understanding only, and no unnecessary limitations should be understood therefrom.

What I regard as new, and desire to secure by Letters Patent, is:

30 1. In a range, an oven-unit comprising a front frame provided with door-openings and having a rearwardly turned outer flange, a top plate having a depressed front marginal portion fitting within said flange and having a downwardly turned attaching flange, side plates having at their upper portions inwardly offset margins and having at their front portions inwardly offset margins provided with inturned attaching flanges, said top plate having depending lateral flanges fitting over the inwardly off-

set upper margins of the side plates, and cap screws connecting said attaching-flanges to said front frame.

2. A range-oven comprising a front frame 45 having a rearwardly turned marginal flange and provided at its inner side with tapped lugs spaced from said flange, side plates having inwardly struck front margins fitting within the lateral flanges of said frame 50 and provided with inturned attaching flanges, said side plates having also inwardly struck upper margins provided with inturned flanges, a top plate having depending lateral flanges embracing the inwardly struck upper margins of the side plates and having a depressed front margin fitting within the top flange of said frame, and provided with a depending attaching flange, and cap screws securing said attaching 60 flange to said lugs.

3. A range-oven comprising a front frame having a rearwardly turned marginal flange and provided at its inner side with tapped lugs spaced from said flange, side plates 65 having inwardly struck front margins fitting within the lateral flanges of said frame and provided with inturned attaching flanges, said side plates having also inwardly struck upper margins provided with 70 inturned flanges, a top plate having depending lateral flanges embracing the inwardly struck upper margins of the side plates and having a depressed front margin fitting within the top flange of said frame and provided with a depending attaching flange, cap screws securing said attaching flanges to said lugs, lining-supporting lugs carried by said front frame, and lining plates engaging said lugs.

AUGUSTUS F. HARTER.
